[57] **CLAIM**

The ornamental design for a powered suction cleaner nozzle, as shown and described.

DESCRIPTION

FIG. 1 is a perspective view of a powered suction cleaner nozzle, showing my new design;

FIG. 2 is a top plan view thereof;

FIG. 3 is a front elevational view thereof;

FIG. 4 is a rear elevational view thereof;

FIG. 5 is a left end elevational view thereof;

FIG. 6 is a right end elevational view thereof;

FIG. 7 is a bottom plan view thereof.

The broken line disclosure of a nozzle coupling in all views is for illustrative purposes only and forms no part of the claimed design.

FIG. I

FIG. 2
